UNITED STATES PATENT OFFICE.

JANNETTE MILLER, OF EAU CLAIRE, WISCONSIN.

DESIGN FOR A PIN OR EMBLEM.

Application filed June 14, 1922. Serial No. 2,683. Term of patent 3½ years.

To all whom it may concern:

Be it known that I, JANNETTE MILLER, a citizen of the United States, residing at Eau Claire, in the county of Eau Claire and State of Wisconsin, have invented a new, original, and ornamental Design for Pins or Emblems, of which the following is a specification, reference being had to the accompanying drawing, forming a part thereof, in which:—

I claim:

The ornamental design for an emblem or pin as shown.

JANNETTE MILLER.

Witnesses:

H. R. GILBERTSON,
A. J. SUTHERLAND.
